UNITED STATES PATENT OFFICE

GEORGE B. STEFFAN, HENRY O. WILLIAMS, AND GLENN H. FLETCHER, OF JOLIET,
ILLINOIS

DESIGN FOR A COMBINED SAFETY ZONE AND TOWER

Application filed November 6, 1930. Serial No. 37,580. Term of patent 3½ years.

To all whom it may concern:

Be it known that we, GEORGE B. STEFFAN, HENRY O. WILLIAMS, and GLENN H. FLETCHER, citizens of the United States, residing at Joliet, in the county of Will and State of Illinois, have invented a new, original, and ornamental Design for a Combined Safety Zone and Tower, of which the following is a specification, reference being had to the accompanying drawing, forming part thereof.

The figure is a view in perspective of a combined safety zone and tower, showing our new design.

The appearance of the tower on the side opposite to that shown in the drawing is substantially the same as that shown. The safety zone is a platform at the base of and joined to the tower.

We claim:

The ornamental design for a combined safety zone and tower, as shown and described.

GEORGE B. STEFFAN.
HENRY O. WILLIAMS.
GLENN H. FLETCHER.
